UNITED STATES PATENT OFFICE.

WILLIBALD TRINKS, OF PITTSBURGH, PENNSYLVANIA, ASSIGNOR, BY MESNE ASSIGNMENTS, TO NATIONAL BRUSH WASHING MACHINE COMPANY, OF PITTSBURGH, PENNSYLVANIA, A CORPORATION OF DELAWARE.

ROLL-STRIPPING MECHANISM.

1,189,640.

Specification of Letters Patent.

Patented July 4, 1916.

Application filed December 9, 1915. Serial No. 65,926.

To all whom it may concern:

Be it known that I, WILLIBALD TRINKS, a citizen of the United States, and residing in the city of Pittsburgh, in the county of Allegheny and State of Pennsylvania, have invented or discovered new and useful Improvements in Roll-Stripping Mechanism, of which the following is a specification.

My invention relates to new and useful improvements in means for the prevention of articles from being wrapped or twisted about rolls or rollers. It is particularly intended for use in connection with the backing roll of a rotary brush washing machine to prevent clothing or other articles being washed from becoming wrapped around the backing roll.

Generally speaking, it comprises a stripper blade provided with a beveled edge which is resiliently pressed against the perimeter of the roll and which is so mounted as to prevent its sagging or bending out of contact with said roll intermediate of its length.

Novel features of construction and arrangement of parts will appear from the following description.

In the accompanying drawings, Figure 1 is a broken end view of a washing machine fitted with my invention; Fig. 2 is a broken plan view of the same; Fig. 3 is an enlarged view showing the relation of the stripper blade to the backing roll; the stripper links being omitted for the sake of clearness; Fig. 4 is a broken front elevation showing one end of the stripper blade dismounted; Fig. 5 is an edge view of one of the links by means of which the backing roll is supported from the machine frame; Fig. 6 is an inner face view of the same; Fig. 7 is an inner face view of one of the stripper links; Fig. 8 is a side view of one of the stripper pins; Fig. 9 is a side elevation of one of the halves of one of the two part bearing blocks of the backing roll, and Fig. 10 is a front view of said bearing block.

The following is a detailed description of the invention.

A represents one of the end plates of a rotary washing machine, the two ends thereof being similar and having journaled be-

tween them the rotary brush B provided with radial bristles 1. Said brush is power driven but, as the method of applying power to the same forms no part of the present invention, it is not shown.

C is the backing roll held resiliently in contact with the brush B and supported in the following manner: The ends of the roll C are each provided with an axial projection, preferably the ball projection 2, which is journaled in the two part socket bearing block 3 which is seated in the annular bearing box 4 formed on the inner face of the suspension link 5, whose upper end is pivoted to the end plate A, as at 6. The outer portion of the annular box 4 is reduced as at 7 65 in external diameter for a purpose to be described. The backing roll C, swingingly supported at both ends, as above described, is held resiliently against the brush B in the following manner, at either side. 8 is a rod 70 whose outer end is pivotally attached to the lower end of the suspension link 5 and whose inner end extends through a hole in the vertical flange 9 of the plate A and is threaded to receive a washer 10 and nut 11. 12 is a 75 helical spring wound about the rod 8 and bearing against the flange 9 and the washer 10, thus exerting resilient pressure to draw the backing roll toward the brush. The tension of the springs at either end of the machine may be regulated by means of the nuts 11. 13 represents one of a pair of links whose upper ends are of annular form, as at 14, to fit over the portions 7 of the bearing boxes 4, thus pivotally supporting said links 85 at their upper ends, one at each end of the backing roll C. The lower ends of said links are solid and enlarged to add weight. Intermediate of their ends each of said links is provided with a threaded hole 15 into which 90 is screwed the threaded portion of the inwardly extending pivot pins 16 whose inner ends are of reduced diameter.

D is the stripper blade, which may be made of any suitable material, preferably hard 95 rubber and whose top edge is beveled to fit snugly against the perimeter of the backing roll C.

17 is an angle bracket whose horizontal web is riveted to the front lower edge of the blade D for the full length of the latter. At its ends the angle of said bracket is 5 spanned by metal holder straps 18 which are curved to form sockets for the ends of the pivot pins 16 whereby said blade is pivotally supported by the stripper links 13. The straps 18 may be brazed to the bracket.

10 19 are leaf springs one of whose ends is soldered or otherwise attached to the horizontal web of the bracket 17 and whose free ends bear against the perimeter of the roll C on the opposite side of its vertical diameter from the blade D. I prefer to provide 15 a leaf spring adjacent to either end of the blade D and one at least intermediate thereof, so that an even resilient pressure is exerted on the blade D throughout its length.

20 It is evident from the foregoing that the blade D is evenly spring pressed throughout its length against the perimeter of the backing roll C and the blade is also stiffened and supported throughout its entire length by 25 the bracket 17 to which the leaf springs are attached. No buckling or sagging of the blade is thus possible but close contact of its entire beveled edge with the roll is insured. The weighted ends of the links 13 30 hold the blade and its mounting in the proper position and prevent the friction of the roll against the stripper blade or the weight of the garments passing between the backing roll and the brush from swinging 35 the stripper blade back around the backing roll. Thus the entrance of garments, or other articles being washed, between the backing roll and the stripper blade is positively prevented and the wrapping of garments 40 around the backing roll rendered impossible.

The suspension of the stripper blade from 45 a point in the axis of the backing roll makes possible continued bearing of the stripper blade against the backing roll under all and any conditions of operation. Let, for instance, the clothes bunch at one end of the roll, forcing the roll away from the brush at that end and practically leaving the roll 50 in contact with the brush at the other end, the stripper blade still remains in contact with the backing roll along its entire length, because by its method of suspension from a point in the axis of the roll, the motion of 55 the blade must identically coincide with the motion of the backing roll.

What I desire to claim is:—

1. In a machine having a roll journaled 60 therein, a stripper mechanism for said roll comprising a blade having its ends pivotally supported from said machine, and resilient members secured to said blade and bearing against the perimeter of said roll whereby

the edge of said blade is spring pressed against said roll, for the purpose described. 65

2. In a machine having a roll journaled therein, a stripper mechanism for said roll comprising a blade, a swinging support for said blade, and resilient members secured to said blade and bearing against the perimeter of said roll whereby the edge of said blade is spring pressed against said roll, for 70 the purpose described.

3. In a machine having a roll journaled therein, a blade, a weighted swinging support 75 for said blade, and resilient members secured to said blade and bearing against the perimeter of said roll whereby the edge of said blade is spring pressed against said roll, for the purpose described.

4. In a machine having a roll journaled therein, a stripper mechanism for said roll comprising a blade, a swinging support for said blade in which the latter is pivotally mounted, and resilient members secured to 85 said blade and bearing against the perimeter of said roll whereby the edge of said blade is spring pressed against said roll, for the purpose described.

5. In a machine having a roll journaled 90 therein, a stripper mechanism for said roll comprising a pair of links having their upper ends pivoted to the machine adjacent to the ends of said roll, a blade having its ends pivotally supported by said links, and 95 resilient members secured to said blade bearing against the perimeter of said roll whereby the edge of said blade is spring pressed against said roll, for the purpose described.

6. In a machine having a roll journaled 100 therein, a stripper mechanism for said roll comprising a pair of links having their upper ends pivoted to the machine adjacent to the ends of said roll, the lower ends of said links being weighted, a blade having 105 its ends pivotally supported by said links, and resilient members secured to said blade and bearing against the perimeter of said roll whereby said blade is spring pressed against said roll, for the purpose described. 110

7. In combination with a machine provided with a frame and a rotary driven member mounted in said frame, a backing roll mounted in said frame in parallelism with said rotary member, means for holding 115 said roll in resilient contact with said rotary member, means for permitting said backing roll to tilt out of parallelism with said rotary member, and a stripper blade pivotally supported from the axis of said backing roll and held resiliently against the perimeter of the latter, for the purpose described.

8. In combination with a machine provided with a frame and a driven rotary member mounted in said frame, a pair of 125 links pivotally attached to said frame, a

backing roll having its ends journaled in said links, spring connection between the free ends of said links and said frame whereby said roll is normally held in resilient contact with said member, a pair of stripper supporting links having their upper ends pivotally attached at the axis of said backing roll at either end of the same, and a

stripper blade mounted on said stripper supporting links and held in resilient contact with the perimetral surface of said backing roll, for the purpose described. 10

Signed at Pittsburgh, Pa. this 29th day of November, 1915.

WILLIBALD TRINKS.
